(57) **CLAIM**

What is claimed is an ornamental design for a battery pack for an external defibrillator, as shown and described herein.

DESCRIPTION

FIG. 1 is a bottom view of the battery pack;

FIG. 2 is a perspective view showing one end of the battery pack of FIG. 1;

FIG. 3 is a perspective view of the battery pack of FIG. 1;

FIG. 4 is a perspective view showing the other end of the battery pack of FIG. 1; and,

FIG. 5 is a side view of the battery pack of FIG. 1.
